ABSTRACT

A mandrel for use in a well tubing in which the mandrel body has an open bore for alignment with the well tubing and a sidepocket offset from the open bore for receiving flow control devices, having a housing for protecting tools in the pocket, having a deflecting guide surface for preventing tools moving in the bore from catching in the mandrel, and being of an extent for receiving and guiding flow control devices into the sidepocket, being of a size to admit and guide only devices seatable in the pocket, and preventing the entrance of open bore tools into the pocket housing. A plurality of identical mandrels with orienting means in the open bore for aligning a flow control device into the housing anpocket with the guide receiving and guiding the flow control device toward and into the pocket.

SIDEPOCKET MANDREL

CROSS-REFERENCE TO RELATED
APPLICATIONS

This application is a continuation in part to my patent application entitled Sidepocket Mandrel, Ser. No. 180,315, filed Sept. 14, 1971 which was copending with and was a continuation in part of patent application entitled Tool Deflecting Mandrel, Ser. No. 154,943, filed June 21, 1971.

BACKGROUND OF THE INVENTION

Generally, a mandrel for use in a well tubing which has an open bore for alignment with the well tubing and an offset or sidepocket for receiving flow control devices such as valves is old as shown in U.S. Pat. Nos. 2,824,525 and 3,268,006. The open bore in the mandrel allows well tools to pass through the well tubing and the mandrel to perform normal well operations below the mandrel even while other operations are being performed by the flow control devices positioned in the sidepocket. However, tools passing through the open bore, for example only, such as on wirelines or pumped hydraulically, may become caught on movement through the mandrel on the sidepocket or on the devices positioned in the sidepocket which may lead to damage of the open bore tools and/or the sidepocket devices and cause the open bore tools to hang in the mandrel. This undesired possibility is aggravated in a slanted well in which the sidepocket is positioned on the low side of the tubing or mandrel.

The present invention is directed to the provision of a deflective guide in the mandrel and in a plurality of identical mandrels for protecting devices in the offset pocket, and for preventing tools moving in the open bores of the mandrels from catching and hanging in the mandrels, and being of a sufficient length to receive oriented flow control devices and guide them into the pockets of the desired mandrel.

SUMMARY

The present invention is directed to a tool deflecting mandrel having a guide means aligned with the offset pocket for protecting flow control devices positioned in the pocket, and preventing tools moving in the well tubing and open bore of the mandrel from catching in the mandrel as they are being moved therethrough, and guiding devices into the sidepocket.

A still further object of the present invention is the provision of a deflector housing aligned with the offset or sidepocket and extending upwardly a distance greater than the distance that any device seated in the offset pocket extends upwardly, thereby preventing any device in the offset pocket from engaging a tool moving through the open bore of the mandrel.

Still a further object of the present invention is the provision of the top of the deflector guide housing extending from the open bore upwardly and outwardly to the inside wall of the mandrel to present a deflecting surface which prevents tools moving in the open bore from catching on the housing or any device seated in the valve pocket.

Yet a still further object of the present invention is the provision of a deflector guide housing above an offset pocket in a mandrel with the housing having an interior and being open adjacent the open bore of the mandrel but of a size to admit only flow control devices into

the pocket and preventing the entrance of open bore tools into the interior of the pocket housing.

Yet a still further object of this invention is the provision of a plurality of identical mandrels each having an orientating sleeve in the open bore of the mandrel above the sidepocket for selectively actuating a flow control device and a deflector guide housing being of sufficient length above the pocket to receive a flow control device when the device is selectively orientated over the desired pocket and thereafter guiding the flow device toward and into the pocket.

BRIEF DESCRIPTION OF THE DRAWINGS

FIG. 1 is a fragmentary elevational view, partly in cross section, illustrating the preferred embodiment of the present invention,

FIG. 2 is an enlarged fragmentary cross-sectional view of the deflector housing of FIG. 1,

FIG. 3 is a cross-sectional view taken along the line 20 3-3 of FIG. 2,

FIG. 4 is a cross-sectional view taken along the line 4-4 of FIG. 2,

FIG. 5 is a cross-sectional view taken along the line 5-5 of FIG. 4,

FIG. 6 is a fragmentary elevational view, partly in cross section, illustrating another form of the present invention,

FIG. 7 is a cross-sectional view taken along the line 7-7 of FIG. 6,

FIG. 8 is an elevational view, partly in cross section, illustrating a flow control device being guided into the embodiment of FIG. 1, and

FIG. 9 is a cross-sectional view taken along the line 9-9 of FIG. 8.

DESCRIPTION OF THE PREFERRED
EMBODIMENT

Referring now to the drawings, and particularly to FIG. 1, the reference numeral 10 generally indicates one of a plurality of identical vertically spaced mandrels for connection in a well tubing 12, only one of which is shown for convenience, and suitably connected therein such as by threaded connections 14. Each mandrel 10 generally includes an open bore 16 aligned with the well tubing 12 for allowing movement of various well tools, such as tool 18, therethrough and includes an offset sidepocket 20 for receiving flow control devices 22, for example only, a gas lift valve.

However, in the past, as various tools such as a tool 18, for example only a valve pulling tool, was lowered through the well tubing 12, for example only such as on a wireline 19, the tool 18 may come in contact with the valve 22 damaging either the valve 22 or the tool 18. In addition, the tool 18 could catch on the valve 22 or on the sidepocket 20, particularly in the case where the well tubing 12 was slanted and the sidepocket 20 was positioned on the low side of mandrel 10. The present invention, as best seen in FIGS. 1-5, provides a deflective guide means, generally indicated by the reference numeral 26, for protecting flow control devices in the offset pocket 20 from damage by tools such as 18 moving in the open bore 16, prevents the tools 18 moving in the open bore 16 from catching on the flow control devices 22 or on the offset pocket 20 as they are moved through the mandrel 10, and guides the oriented and released flow control devices toward the sidepocket 20. The deflective guide means 26 is positioned in the man-

drel and its axis is aligned with the axis of the offset pocket 20, and as best seen in FIG. 1, extends upwardly a distance greater than the distance that any device 22 seated in the offset pocket extends upwardly thereby isolating any device 22 seated in the pocket 20 from any tool 18 moving through the open bore 16. Thus the guide means 26 has an interior 33 which will enclose and entirely protect any flow control device 22 seated in the sidepocket 20. In addition the interior 33 is sized to receive any sidepocket device 22, but is generally smaller than the tools 18. For convenience of manufacture, the deflective guide means 26 may be an insert which may be welded into place in the mandrel by welds 28, as best seen in FIG. 2, at a position above a valve latching shoulder 30.

The top 32 of the guide means 26 may extend from the open bore 16 in the mandrel upwardly and radially outward from the open bore 16 entirely to the inside 31 of the wall of the mandrel 10, for example on an upwardly tapering angle of 30 degrees from the vertical, to present an upwardly deflecting surface 32. The surface 32 deflects tools 18 which move downwardly in the well tubing 12 and open bore 16 away from the valve pocket 20 and into the open bore 18 and prevents the tools 18 from making any damaging contact with a sidepocket device 22 or from catching on the device 22 or on the valve pocket 20. The guide means 26 shown in FIGS. 1-5 may be generally U-shaped in cross section and may have an opening 34 adjacent the open bore 16 but of a size for admitting only devices 22 which are seated in the offset pocket 20 and is sized to prevent the entrance of larger open bore tools 18 into the interior 33 of the guide means 26 and sidepocket 20. Thus, as best seen in FIG. 3, a device 22 may be readily positioned in the opening 34 and into the interior 33 of the guide means 26, but a well tool 18 traveling through the open bore 16 is prevented from entrance therein or contact with the sidepocket device 22.

Referring now to FIGS. 6 and 7, another embodiment is shown which includes side guide rails 40, which for example only may be angle shaped in cross section, enclosing the interior 33 for performing the same function and result. As in the preferred embodiment, the guide rails 40 extend upwardly from the pocket 20 a distance greater than the height of any device 22 seated in the offset pocket 20 to isolate the device 22 from any tool 18 moving through the well bore 16. And the tops 42 of the guide rails 40 extend upwardly and outwardly from the open bore 16 to present a deflecting surface 42 which prevents any tools 18 moving down the well bore 16 from catching either on the sidepocket device 22 or the sidepocket housing 20 and instead guides such tools 18 into the bore 16. And the guide rails 40 by being positioned on either side of the sidepocket provide an opening adjacent the open bore 16 of a size to admit sidepocket devices 22, but prevent the entrance therein of larger well tools 18.

Of course, in either embodiment if the deflector guide means 26 extends upwardly far enough such that the top therof is shielded from the open bore 16 by the top of the mandrel 10, the top deflecting surfaces 32 and 42 may be omitted. That is, there will not be sufficient space between the top of the mandrel and the top of the guide means 26 whereby tools 18 of limited flexibility can enter and become caught.

Either the embodiment of FIGS. 1-5 or 6-7 may be provided, as shown with an orientating sleeve 46 positioned in the open bore 16 and above the sidepocket 20. The sleeve 46 includes an upwardly directed helical surface 48 and longitudinal slot 49 for rotational orientating a kickover tool for properly aligning a flow control device for insertion into one of the sidepockets 20 in any selected mandrel 10. Referring now to FIGS. 8 and 9, the installation of a flow control device 22 into the sidepocket 20 by means of a kickover tool 50, such as one more fully described in copending patent application Ser. No. 95,408, filed Dec. 4, 1970 entitled Apparatus for Installing and Removing Flow Valves, is best seen. Thus, when the kickover tool is raised in the bore 16, the key 52 will contact the surface 48 and orient the attached flow control device 22 over the pocket 20 in the desired mandrel in the tubing 12. It is to be noted that the deflector guide means 26 acts to laterally retain and guide the flow control device 22 when the flow control device is oriented in the proper position above the selected sidepocket 20 and positively guides the device 22 as it is moved downwardly and into the pocket 20. Of course, the deflector 26 should extend a sufficient distance above the sidepocket 20 so as to receive and guide the flow control device 22 when it is oriented. It is to be noted that a plurality of identical mandrels 10 may be used in the tubing 12 allowing all of the mandrels to be similarly manufactured and requiring only a minimum of stocking requirements at the place of use as compared to those devices in which require variations in structure to obtain selective installation and removal of flow control devices in a particular mandrel 10.

In use, flow control devices 22 may be conventionally installed and removed from the offset pocket 20 of any desired mandrel. And when it is desired to move other types of working tools, such as 18, through the well tubing 12 and the open bore 16, such an operation may be performed without the tools 18 engaging the devices 22 causing damage to one or the other or without the tools 18 hanging on the device 22 or the sidepocket 20. Since the deflector guide means 26 extends upwardly a distance greater than the distance that any device 22 seated in the sidepocket extends upwardly, the device 22 will be enclosed, protected and isolated from any tool 18 moving in the bore 16. Also, the tool 18 as it is lowered will contact the deflective guide means 26 and will be deflected inwardly by the deflecting faces 32 and 42 into the bore 16 and away from the offset pocket 20. And because the opening 34 and the interior 33 of the guide means 26 is sized to admit only flow control devices seatable in the pocket 20, the well tools 18 are kept in the open bore 16 and prevented from engaging any flow control devices 22 positioned in the offset pocket 20. And the deflector guide means 26 acts to positively guide the orientated flow control devices 22 into the sidepocket 20 as they are installed.

The present invention, therefore, is well adapted to carry out the objects and attain the ends and advantages mentioned as well as others inherent therein. While presently preferred embodiments of the invention are given for the purpose of disclosure, numerous changes in the details of construction, and arrangement of parts, may be made which will readily suggest themselves to those skilled in the art and which are encompassed within the spirit of the invention and the scope of the appended claims.

What is claimed is:

1. A well installation comprising,
a well tubing having a plurality of identical mandrels
each having an open bore for alignment with the
well tubing and a pocket offset from the open bore
for flow control devices,
5
a deflector guide means including a housing aligned
with the pocket and extending outwardly a distance
greater than the distance any device seated in the
pocket extends outwardly from the pocket,
said housing being open adjacent the open bore but
of a size for admitting and guiding only pocket de-
vices into the pocket and preventing the entrance
of open bore tools into said pocket housing, and
the end of the housing extending from the open bore
15 upwardly and radially outwardly to the inside wall
of the mandrel thereby presenting a deflecting sur-
face which prevents tools in the open bore from
catching on the housing or on any device in the
pocket.
2. The apparatus of claim 1 wherein the deflector
housing includes,
a guide rail on each side of the axis of the offset
20 pocket.
3. The apparatus of claim 1 wherein the top of the de-
flector housing extends upwardly adjacent the top of
the mandrel whereby the space therebetween is insuffi-
cient for entrance therein by an elongate tool.
25
4. The apparatus of claim 1 wherein the deflector
housing is U-shaped in cross section.
30
5. The apparatus of claim 1 including,
an orientating sleeve in the open bore for aligning a
flow control device into the housing and into the
pocket,
said housing extending a sufficient length from the
35 pocket to receive the flow control device when the
flow control device is orientated into alignment
with the pocket and thereafter guide the flow con-
trol device toward and into the pocket.
6. In a mandrel for use in a well tubing in which the
40 mandrel body has an open bore for alignment with the
well tubing and a pocket offset from the open bore for
flow control devices, the improvement of a deflective
guide means for protecting the devices in the pocket
and preventing open bore tools moving in the bore
45 from catching in the mandrel comprising,
a deflector housing aligned with the pocket and ex-
tending upwardly a distance greater than the dis-
tance any device seated in the pocket extends,
the top of the housing extending from the open bore
50 upwardly and radially outwardly from the open
bore to the inside wall of the mandrel thereby pres-
enting a deflecting surface which prevents tools in
the open bore from catching on the housing or on
any device in the pocket,
said housing being open adjacent the open bore but
55 of a size to admit only flow control pocket devices
and preventing the entrance of open bore tools into
said pocket housing,
an orientating sleeve in the open bore above the
60 pocket for aligning a flow control device into the
housing and over the pocket,
said housing extending a sufficient length above the
pocket to receive the flow control device when the
flow control device is orientated over the pocket
65 and thereafter guide the flow control device toward
and into the pocket.

7. A well installation comprising,
a well tubing having a plurality of identical mandrels
each having an open bore for alignment with the
well tubing and a pocket offset from the open bore
for receiving flow control devices and including an
orientation sleeve mounted in the open bore for co-
acting with a flow control handling apparatus,
each said sleeve including a longitudinally directed
10 orientation slot angularly spaced from the axis of
the offset pocket a predetermined amount,
a guide surface positioned below each said slot and
directed upwardly and inwardly toward the bottom
of said slot,
a shoulder positioned at the top of and entirely block-
ing the slot, for orientating a flow control handling
device,
a deflector guide means including a housing aligned
with the pocket and extending upwardly a distance
greater than the distance any device seated in the
pocket extends upwardly,
15 said housing being open adjacent the open bore but
of a size for admitting only flow control devices
into the pocket and preventing entrance of open
bore tools into said pocket housing,
the top of the housing extending from the open bore
upwardly and radially outwardly to the inside wall
of the mandrel thereby presenting a deflecting sur-
face which prevents tools in the open bore from
catching on the housing or on any device in the
pocket, and
20 said housing extending a sufficient length above the
pocket to receive a flow control device when the
flow control device is oriented over the pocket and
thereafter guide the flow control device toward and
into the pocket.
8. A mandrel for use in a well tubing comprising, a
mandrel body having an open bore for alignment with
the well tubing,
a valve pocket in said body offset from the open bore
25 for receiving flow control devices,
an orientation sleeve positioned in the open bore for
orientating and releasing a flow control handling
apparatus, each said sleeve including a longitudi-
nally directed orientation slot angularly spaced
from the axis of the offset valve pocket a predeter-
mined amount,
a deflector guide means including a housing aligned
with the pocket and extending upwardly a distance
30 greater than the distance any flow control device
seated in the pocket extends upwardly,
the top of the housing extending from the open bore
upwardly and radially outwardly toward the inside
wall of the mandrel for presenting a deflecting sur-
face which prevents open bore tools from catching
on the housing or on any device in the pocket,
said housing being open adjacent the open bore but
35 of a size for admitting only flow control devices
into the pocket and preventing entrance of open
bore well tools into said pocket housing, said hous-
ing extending a sufficient length above the pocket
to receive a flow control device when the flow con-
trol device is oriented over the pocket whereby the
40 housing guides the lower end of the flow control device toward and
into the pocket as the flow control handling appa-
ratus moves along the longitudinal slot.
